US00D948247S

(12) **United States Design Patent** (10) Patent No.: **US D948,247 S**
Bosstick (45) Date of Patent: **** Apr. 12, 2022**

(54) **INFLATABLE AIRCRAFT BED**

(71) Applicant: **JetBed, Inc.**, San Diego, CA (US)
(72) Inventor: **Gerald Bosstick**, Rancho Santa Fe, CA (US)
(73) Assignee: **JetBed, Inc.**, San Diego, CA (US)
(**) Term: **15 Years**
(21) Appl. No.: **29/755,388**
(22) Filed: **Oct. 20, 2020**
(51) LOC (13) Cl. **06-09**
(52) U.S. Cl. **USPC D6/604**

(58) **Field of Classification Search**

(57) **CLAIM**

The ornamental design for an inflatable aircraft bed, as shown and described.

DESCRIPTION

FIG. 1 is a top perspective of the aircraft bed.
FIG. 2 is a bottom perspective of the aircraft bed.
FIG. 3 is a top view of aircraft bed.
FIG. 4 is a bottom view of the aircraft bed.
FIG. 5 is a right-side view of the aircraft bed.
FIG. 6 is a left-side view of the aircraft bed.
FIG. 7 is a rear view the aircraft bed; and,
FIG. 8 is a front view the aircraft bed.
